ABSTRACT OF THE DISCLOSURE

A method for combatting harmful microorganisms, such as fungi and bacteria, by applying a 2-(2'-hydroxyphenyl)-oxazole.

CROSS-REFERENCE TO RELATED APPLICATION

This is a continuation-in-part of our application Ser. No. 686,298, filed Nov. 28, 1967, now abandoned.

BACKGROUND OF THE INVENTION

The present invention provides a method for combating harmful microorganisms, which comprises applying to a desired site an effective amount of a 2-(2'-hydroxyphenyl)-oxazole of the formula

(1)

or an alkali metal salt thereof, where R is an aromatic ring system containing at most 2 six-membered rings, which is fused on as indicated by the valency lines, and X represents a benzene residue substituted by a hydroxyl group in ortho-position relatively to the bond with the oxazole ring.

Of special value are 2-(2'-hydroxyphenyl)-oxazoles of the formula

(2)

in which R has the above meaning, Me is a hydrogen or alkali metal atom, and at least one of the symbols X₁ and X₂ represents a halogen atom, an amino group or an alkyl group containing up to 4 carbon atoms and the other is a hydrogen or halogen atom or an alkyl group with up to 4 carbon atoms. The present invention is specially concerned with a method for combating harmful micro-

2

organisms by applying a 2-(2'-hydroxyphenyl)-oxazole of the formula

(3)

in which Me has the above meaning; at least one of the symbols X₃ and X₄ stands for a halogen atom or an alkyl group with up to 4 carbon atoms and the other for a hydrogen or halogen atom or for an alkyl group with up to 4 carbon atoms, and one to four of the symbols R₁ to R₄ represent hydrogen or halogen atoms and two of these symbols, not standing for hydrogen or halogen atoms, represent phenyl, alkyl, alkoxy, phenylalkyl, cyclohexyl, nitro, primary amino, alkylamino, acylamino, trihalomethyl, aminosulphonyl, methylaminosulphonyl groups or sulphonic acid groups (possibly in the form of their alkali metal salts); or two vicinal symbols R₁ to R₄ together form the complement to a fused-on carbocycle, which is preferably unsubstituted, and any alkyl carbon chains in the substituents contain at most 12 carbon atoms. Within the indicated meanings R₁ to R₄ may be chosen independently of one another, that is to say for instance that one and the same molecule may contain 1 to 4 halogen atoms side by side with 0 to 3 hydrogen atoms and 0 to 2, preferably 0 to 1, of the other substituents of the kinds indicated above.

Preferred compounds are the 2-(2'-hydroxyphenyl)-benzoxazoles of the formula

35 (4)

40

where Me₁ is a hydrogen, sodium or potassium atom; one to three of the symbols R₅ to R₇ are hydrogen or halogen atoms and one or two of them that do not represent hydrogen or halogen atoms stand for phenyl, alkyl, alkoxy, phenylalkyl, cyclohexyl, nitro or sulphonic acid groups, and the alkyl carbon chains in the substituents contain at most 12 carbon atoms; X₃ represents a hydrogen or halogen atom or an alkyl group with 1 to 4 carbon atoms, and X₄ a halogen atom.

Particularly suitable for the purpose mentioned above are compounds of the formula

55 (5)

60

in which one or both of the symbols R₈ and R₉ are hydrogen, chlorine or bromine atoms, methyl, methoxy or nitro

groups and, when one of these symbols does not satisfy this definition, it stands for a phenyl, cyclohexyl group or a phenylalkyl group containing up to 9 carbon atoms; R_{10} represents a hydrogen or halogen atom; X_6 a hydrogen, chlorine or bromine atom or a methyl group and X_7 a chlorine or bromine atom.

In this group 2-(2'-hydroxyphenyl)-benzoxazoles of the formula

(6)

where R_{11} is a hydrogen, chlorine or bromine atom, an alkyl group with 1 to 4 carbon atoms, a phenyl, cyclohexyl or methoxy group; R_{12} represents a hydrogen, chlorine or bromine atom or a methyl group; R_{13} a hydrogen, chlorine or bromine atom, and X_8 and X_9 a chlorine or bromine atom each—are particularly valuable as active ingredients of antimicrobial preparations.

More especially, 2-(2'-hydroxyphenyl)-benzoxazoles of the formula

(7)

where R_{14} is a hydrogen, chlorine or bromine atom, a methyl, phenyl or cyclohexyl group, and where R_{12} , R_{13} , X_8 and X_9 have the above meanings—are preferred because of their good antimicrobial activity. Extremely satisfactory results in combating microorganisms have been obtained with 2-(2'-hydroxyphenyl)benzoxazoles of the formula

(8)

where R_{15} and R_{16} each is a hydrogen, chlorine or bromine atom or a methyl group, and R_{13} , X_8 and X_9 have the above meanings. Specifically, the following compounds may be mentioned, for example:

(9)

(10)

and

(11)

which display an excellent activity against microorganisms, especially against bacteria.

The 2-(2'-hydroxyphenyl)-oxazoles of the Formula 1 can be prepared by known methods by cyclizing an ortho-hydroxyamino compound of the formula

5

where R has the above meaning—with a functional derivative of a 2-hydroxybenzene-1-carboxylic acid
(HOOC—X)

and, if desired, introducing further substituents, for example halogen atoms or sulphonate acid groups, into the resulting oxazole compound and/or converting it into an alkali metal salt thereof.

An especially unexpected feature of the compound of the Formula 1 is their broad antibacterial activity spectrum which, in the case of some of these oxazoles, extends to both Gram-positive and Gram-negative bacteria. In this connection, as far as their application is concerned, the absence of odours and colours in the compound of the Formulas 1 to 11 is of special value.

The present invention includes also the use of the 2-(2'-hydroxyphenyl)-oxazoles in pest control quite generally. The antimicrobial compounds may be used on a very broad basis, especially for protecting organic substrates from infestation by destructive and pathogenic (including phytopathogenic) microorganisms. Accordingly, the aforementioned compounds may be used as preservatives or disinfectants for textile materials and other industrial products of many kinds, in plant protection, agriculture, veterinary medicine and cosmetics.

From among non-textile industrial products that can be protected with the aid of the oxazoles the following random examples may be given: Textile assistants and improving agents, glues, binders, paints, dyeing and printing pastes and similar preparations based on organic or inorganic dyestuffs or pigments, including those which contain a share of casein or other organic compounds. Likewise, wall and ceiling paints, for example those containing a proteinic dyestuff binder, may be protected from infestation by pests by the addition of the new compounds. Timber may likewise be protected.

Furthermore, the oxazoles may be used for producing preserving and disinfecting finishes on fibres and textile materials, including both natural and synthetic fibres on which they produce a durable protection against harmful (including pathogenic) microorganisms, for example fungi and bacteria. The compounds may be added before, during or after a treatment of such textile materials with other substances, for example dyeing or printing pastes, dressing agents etc.

Textile materials treated in this manner are also protected against body odour (perspiration) caused by microorganisms.

The oxazoles may also be used as preservatives in the cellulose and paper industry, inter alia for preventing the known slime formation in paper-making machines due to microorganisms.

Furthermore, when the oxazoles are combined with surface-active, especially detergent, substances, there are obtained detergents and cleansing agents having an excellent antibacterial or antimycotic effect. The compounds of the Formulae 1 to 11 can be incorporated, for example, with soaps, or combined with soap-free detergents or surface-active substances or they may be combined with mixtures of soaps and soap-free detergents, and their antimicrobial activity is fully maintained in such combinations.

Cleansing preparations containing compounds of the formulae shown above may also be used in industry and the home, in the food industry, for example in dairies, breweries or abattoirs. They may also be used as ingredients of preparations used for cleansing or disinfecting hospitals or surgeries.

75

The effect of the oxazoles can also be utilized in providing plastic materials with a preserving and disinfecting finish. When plasticizers are used it is advantageous to dissolve or disperse the antimicrobial compound in the plasticizer and then to incorporate it with the plastic material. It is advantageous to ensure that the additive is as evenly as possible distributed in the plastic material. Plastic materials having antimicrobial properties can be used for making utilitarian articles of all kinds in which an activity against a wide variety of germs, for example bacteria and fungi, is desirable, for example in doormats, bathroom curtains, seats, treads in swimming baths, wall coverings or the like. By incorporation with waxes and polishing compositions, floor and furniture polishes are obtained that have a disinfecting activity.

The antimicrobially active substances can be applied to the textile materials to be protected in a variety of ways, for example by impregnating or spraying with solutions or suspensions containing the above-mentioned compounds as active ingredients. Depending on the individual use, the content of active substance may vary from 1 to 30 g. per litre of treatment liquor.

In most cases textile materials of synthetic or natural origin will be adequately protected from infestation by fungi and bacteria by application of a preparation containing 0.1% to 3% of active substance. The active substances mentioned above may be used in combination with other textile assistants such as dressing agents, anti-crease finishing agents or the like.

The form in which the active substances of this invention are applied may be similar to the conventional formulations of pesticidal preparations; for example, preparations containing the said active substances may, if desired, further contain additives such as vehicles, solvents, diluents, dispersants, wetting agents, adhesives or the like and also other pesticides.

Unless otherwise indicated, parts in the following manufacturing instructions and examples are by weight.

MANUFACTURING INSTRUCTIONS

(A) A mixture of 20.7 parts of 3,5-dichlorosalicylic acid, 12.3 parts of 2 amino-4-methylphenol and 100 parts of polyphosphoric acid is stirred and heated for 3 hours at 195–200° C. under nitrogen. The reaction mixture is then poured in a thin jet over 2000 parts of ice water and the resulting suspension is stirred for 1½ hours. The compound A of the formula

(13)

is filtered off, washed neutral with water and dried. Yield: 28 parts. Melting point: 158–160° C. After purification by recrystallization from chloroform+petroleum ether the compound melts at 160–161° C.

(B) A mixture of 20.7 parts of 3,5-dichlorosalicylic acid, 14.4 parts of 2-amino-4-chlorophenol and 0.4 part of aluminium chloride in 140 parts by volume of o-dichlorobenzene is mixed at 130° C. within 30 minutes with a solution of 12 parts of phosphorus trichloride in 10 parts by volume of o-dichlorobenzene. The reaction mixture is then refluxed for 2 hours and poured over ice water. The aqueous layer is separated and the organic phase repeatedly washed with water. The o-dichlorobenzene is expelled with steam, to leave the compound B of the formula

(14)

in a yield of 22 parts, melting at 199–201° C. After recrystallization from dioxane+methanol the compound melts at 204–205° C.

(C) 32.0 parts of bromine in 50 parts by volume of glacial acetic acid are added at 50–60° C. within 80 minutes to a solution of 21.1 parts of 2-(2'-hydroxyphenyl)-benzoazazole in 150 parts by volume of glacial acetic acid. The resulting suspension is heated for 2 hours longer at 60° C., then cooled and at 25° C. 200 parts of water are added. The compound C of the formula

(15)

is filtered off, rinsed with water and dried. Yield: 34 parts. After recrystallization from dioxane+acetonitrile or from dimethylformamide the compound melts at 203–204° C.

(D) 56.0 parts of the compound of the formula

(16)

(=Compound F in the Table)

are stirred within 40 minutes into 130 parts by volume of chlorosulphonic acid. The temperature of the mixture rises gradually to 45–50° C., and a clear solution is obtained which is heated for 2 hours at 105–110° C. and then poured in a thin jet over ice water. The precipitated compound of the formula

(17)

is filtered off, rinsed with water and dried. Yield: 70 parts. After recrystallization from dioxane the compound melts at 264–266° C.

$C_{13}H_6O_4NSCl_3$.—Calculated (percent): C, 41.24; H, 1.60; N, 3.70. Found (percent): C, 41.36; H, 1.73; N, 3.70.

(E) A solution of 18.9 parts of the sulphochloride in 50 parts by volume of dimethylformamide is refluxed for 3 hours and then cooled to 25° C., whereupon the compound of the formula

(18)

settles out in light-yellow flakes melting at 226–228° C. Yield: 17 parts.

A mixture of 4.05 parts of the dimethylamine salt and 20 parts by volume of 2 N sodium hydroxide solution is heated for 15 minutes on a water bath, during which dimethylamine is given off. The solution is cooled to 25° C. and acidified with 2 N hydrochloric acid. The precipitate is filtered off and once recrystallized from aqueous alcohol, to yield about 2.6 parts of the compound D of the formula

(19)

melting above 400° C.

(F) A solution of 6.29 parts of the compound of the Formula (13) in 100 parts by volume of dimethylformamide is mixed at 90° C. with a solution of 0.8 part of sodium hydroxide in 3.0 parts by volume of water. The

heating bath is removed and 100 parts by volume of alcohol are added at 45° C. The compound E of the formula

(20)

begins to settle out slowly. The reaction mixture is cooled to 5° C. and the product filtered off and dried; it melts above 400° C. Yield: 5.4 parts.

As described in manufacturing instructions A to E above, the 2-(2'-hydroxyphenyl)benzoxazoles F to Z, AA to BB of the following table can be prepared; they correspond to the above Formula 3 and the symbols R₁ to R₄, X₁ and X₂ have the meanings shown in the table.

EXAMPLE 1

Determining the minimal inhibitory concentration (MIC) against bacteria in the dilution test

The MIC (minimal inhibitory concentration) is determined by a method adapted from the standard procedure, which furnishes an approximation to absolute minimal inhibitory values of an active substance.

A solution of 1% and 0.3% strength each of the above substances in dimethylsulphoxide are poured into small tubes containing glucose broth and with these solutions dilution series are prepared in which each member is a tenfold dilution of the preceding one. By combining the two series, the following continuous dilution series is obtained: 1000, 300, 100, 30, 10, 3 parts per million and so on.

The solutions are inoculated with *Staphylococcus aureus* and then incubated for 48 hours at 37° C. (bacteriostatic test).

After the time mentioned, the minimal inhibitory values in parts per million, shown in the following table, are found:

Compound:	Minimal inhibitory concentration (MIC) ¹
A	1
B	1
F	10
G	0.1
J	0.1
L	300
M	10
N	100
O	1
S	100
T	100
U	300
V	10
W	10
X	300
Y	300
Z	30

¹ In parts per million bacteriostatic test, *Staphylococcus aureus*.

EXAMPLE 2

35 Antibacterial soaps in cake form are manufactured by adding 1.2 g. of a compound of the Formula 1 to the following mixture:

120 g. of basic soap in flake form
40 0.12 g. of the disodium salt of ethylenediamine tetra-acetic acid (dihydrate)
0.24 g. of titanium dioxide
6 g. ethyleneglycol

45 The soap chips obtained by rolling are disintegrated in a high-speed stirrer and then moulded into cake form.
2.5 grams of the antimicrobial soaps are dissolved in 50 ml. of sterile tap water and 1 ml. of the solution is added to 4 ml., to 1.5 ml. and 3.5 ml. of sterile brain heart infusion broth. By continuously diluting each member to ten times the preceding member in the series there are obtained two dilution series which by combination furnish the following continuous dilution series: 100, 30, 10, 3, 1, . . . and so on, parts per million of active substance.

50 55 The solutions are inoculated with the bacteria *Staphylococcus aureus*, *Escherichia coli*, and incubated for 24 hours at 37° C. After this time, 0.05 ml. is withdrawn with a pipette from each solution and poured out over brain heart infusion slant-agar. The agar tubes are then incubated for another 24 hours at 37° C., and then the minimal lethal concentration in parts per million is determined.

Compound	<i>Staphylococcus aureus</i>	<i>Escherichia coli</i>
A	100	100
B	10	100
G	10	>100
J	100	100

EXAMPLE 3

Specimens of a woolen fabric are impregnated with an 0.1% solution of a compound of the Formula I in dioxane and then padded to a liquid content of 100%. The dried fabric specimens contain 0.1% active substance, referred 75 to their own weight.

11

To test the effect against bacteria round blanks of 10 mm. diameter of the impregnated fabrics are placed on glucose agar plates, which have previously been inoculated with *Staphylococcus aureus*, and the plates are then incubated for 24 hours at 37° C.

The valuation extends, on one hand, to the inhibitory zones (IZ in mm.) found around the blanks and, on the other hand, to the growth (G%) detected underneath them by microscopic examination:

Staphylococcus aureus		
Compound	IZ (mm.)	G, percent
B-----	4	0
G-----	4	0

What is claimed is:

1. A method for combatting bacteria which comprises applying to said bacteria an anti-bacterially effective amount of a 2-(2'-hydroxyphenyl)-benzoazole of the formula

in which R₁₁ represents a member selected from the group consisting of hydrogen, chlorine, bromine, alkyl with up to 4 carbon atoms, phenyl, cyclohexyl and methoxy, R₁₂ represents a member selected from the group consisting of hydrogen, chlorine, bromine and methyl and R₁₃ is hydrogen, chlorine or bromine and X₈ and X₉ represent chlorine or bromine each.

2. The method of claim 1, wherein the 2-(2'-hydroxyphenyl)-benzoazole has the formula

12

in which R₁₄ represents a member selected from the group consisting of hydrogen, chlorine, bromine, methyl, phenyl and cyclohexyl.

3. The method of claim 1, wherein the 2-(2'-hydroxyphenyl)-benzoazole has the formula

15 in which R₁₅ and R₁₆ each stands for a member selected from the group consisting of hydrogen, chlorine, bromine and methyl.

4. The method of claim 3, wherein the 2-(2'-hydroxyphenyl)-benzoazole has the formula
